CLAIM

The ornamental design for a leg brace as shown and described.

DESCRIPTION

FIG.1 is a perspective view of a leg brace showing my new design;

FIG.2 is a front view thereof;

FIG.3 is a rear view thereof;

FIG.4 is a left view thereof;

FIG.5 is a right view thereof;

FIG.6 is a top view thereof;

FIG.7 is a bottom view thereof;

FIG. 8 is a top view of the leg brace of FIG. 1, shown in a first condition of use for clarity of disclosure; and,

FIG. 9 is a perspective view of the leg brace of FIG. 1, shown in a second condition of use for clarity of disclosure. In the drawings, the equal-length broken lines depict portions of the leg brace that form no part of the claimed design. The dash-dot-dash broken lines depict the surface shading of the leg brace that form no part of the claimed design. All broken lines form no part of the claimed design.

1 Claim, 9 Drawing Sheets
